COMBINATION CURLER AND WAVER

Adelard Hormidas Rivard, Detroit, Mich.

Application September 3, 1947, Serial No. 771,895

1 Claim. (Cl. 132—44)

1

My present invention relates generally to the class of toiletry devices of the hair curling and waving type, and more specifically to an improved combination curler and waver including a curling mandrel for the free ends of a strand of hair, and a flexible and reversible waving form for the rooted portions of the strand, whereby the hand manipulated device may be utilized and fastened in the hair to produce an outer set of artistic curls and a similar set of waves nearer the scalp.

The combination curler and waver includes a minimum number of parts that may with facility be manufactured with low cost of production, and the parts may be assembled with convenience, to constitute a device of this character that may be manipulated with facility for artistic hair dressing.

The invention consists in certain novel features of construction and combinations and arrangements of parts as will hereinafter be described, and more particularly set forth in the appended claim.

In the accompanying drawings I have illustrated a complete example of a physical embodiment of my invention in which the parts are combined and arranged in accord with one mode I have devised for the practical application of the principles of the invention. It will however be understood that changes and alterations are contemplated and may be made in these exemplifying drawings and mechanical structures, within the scope of my claim, without departing from the principles of the invention.

Figure 1 is a plan view in extended shape of a combined curler and waver in which my invention is embodied.

Figure 2 is an edge view of one of the devices.

Figure 3 is a longitudinal sectional view of the device.

Figure 4 depicts the combination device in position to form a curl and a wave and as suspended in the hair; and Figure 5 is an end view showing the dual fastening means for the device.

In carrying out my invention I employ a curling mandrel 1, of rubber or other suitable material, preferably cylindrical in shape, about which the free end of a strand or twist of hair is wound to provide a curl, and to one end of the mandrel a flexible flat plastic or spring metal strap 2 is attached to form the wave-form about which the root ends or scalp ends of hair are wrapped to provide a wave adjoining the curl. The strap 2 which must be flexible to permit its bending as shown in Fig. 4 is made of spring metal, a suitable

2

plastic or of rubber, all of the aforementioned materials having been used with equal success.

The end of the wave-form or tongue 2 may be affixed to the mandrel in suitable manner, as by fastening the end of the strap in the slotted tapered end 3 of the mandrel and firmly securing together the connected parts.

The wave-form or flat flexible strap is provided with a longitudinal series of spaced vent holes or 10 perforations 4 to afford ventilation from within the wrapped wave on the form, and the opposite side edges of the form are notched or scalloped, as at 5 and 6, to assist in retaining the wrapped hair on the form and holding the hairs in place, and 15 these two series of notches or serrations preferably terminate short of the free end of the form, to limit the width of the wave and permit the use of the free end of the strap in attaching it to the mandrel, as in Fig. 4.

20 In actual practice, after a portion of the hair has been wrapped about the mandrel to form a curl, and the inner adjoining portion of the hair has been wrapped about the form to provide the wave, the flexible and reversible strap is manipulated to form a loop as 7 in Fig. 4 and then the free end of the wave-form or strap is coupled or attached by a quick-detachable fastener to the mandrel, for suspending and retaining the device in correct position in the hair.

25 The flexible wave-form, strap, or tongue is reversible for convenience in curling and waving the hair, and to this end a duplex or dual fastening member is mounted on the mandrel for selective use by the free end of the wave-form.

30 This dual fastener includes a buckle 8 fastened in or affixed to a tapered end 9 of the mandrel, and a pair of buckling loops or sockets 10 and 11, one at each side of the buckle, are selectively used to receive the free end of the wave-form.

35 From this description, taken in connection with my drawings, it will be apparent that the combination curler and waver may readily be manipulated for curling and waving the hair, and of course a number of the devices are utilized in a 40 hairdressing operation; and further it will be apparent that the devices may be produced in various sizes and shapes to be employed in the formation of curls and waves in the hair.

Having thus fully described my invention what 45 I claim as new and desire to secure by Letters Patent is:

In a hair curler and wave former, the combination which comprises a comparatively short cylindrical mandrel about which hair is wrapped, a substantially flat wave form of flexible material

carried by and extended from one end of the said mandrel whereby the said wave form may be folded over either side of the mandrel, said wave form having a V-shaped outer end to facilitate inserting the end in holding means and having scallops in the edges, and also having perforations therethrough for providing ventilation from within with hair wrapped on said wave form, said wave form providing means for wrapping the roots of the hair adjacent the scalp, and a buckle 10 including a plate with transverse straps on both sides thereof extended from the opposite end of the mandrel with the straps providing sockets positioned to receive the end of the wave form whereby the said wave form may be bent around 15 in either direction and inserted in a socket on either side of the buckle plate and thereby tem-

porarily held on either side of the curler by one of the said straps.
